POCKETKNIFE

Herbert William Miller, Burbank, Calif.

Application March 18, 1940, Serial No. 324,610

7 Claims. (Cl. 30—164)

This invention relates generally to articles having handles, and more particularly to articles of hardware such as pocket knives.

An object of the invention is to provide a pocket knife or similar handled article, embodying means correlated with the handle thereof, which is easily detachable from the handle for use as blade sharpening element in one of its adaptations, and which, in its applied position on the handle, is securely locked in place without extraneous fastening means and in a manner not to detract from the appearance of the article or affect its usual dimensions, all to the end of providing an extremely simple and inexpensive attachment which is instantly available whenever it is desired to sharpen a blade of the knife.

Another object of the invention is to provide an attachment of the above described character which can be readily applied to pocket or other knives as at present manufactured, with but a negligible difference in the cost of the article; which is detachably secured to the handle of a knife by concealed fastening means; which does not present any parts projecting from the handle; which compensates and can be easily adjusted for any wear occurring on its fastening means; and which can be replaced at slight cost should its sharpening element become unfit for use.

With these and other objects in view, the invention resides in the combinations and arrangements of elements as set forth in the following specification and particularly pointed out in the appended claims.

In the accompanying drawing:

Figure 1 is a view in front elevation of a pocket knife embodying this invention;

Figure 2 is a view of the pocket knife in side elevation;

Figure 3 is an enlarged sectional view taken on the line 3—3 of Figure 1, and showing the attachment embodying this invention locked in place on the pocket knife;

Figure 4 is a view similar to Figure 3 and showing the attachment released from the pocket knife;

Figures 5 and 6 are detail views in elevation showing the obverse and reverse sides of the attachment;

Figure 7 is a view in front elevation of a pocket knife embodying a modified form of the invention;

Figure 8 is a view showing the pocket knife of Figure 7 in side elevation.

Referring specifically to the drawing, and particularly to Figures 1 to 6, inclusive, this embodiment of the invention is shown for the purpose of illustration applied to a conventional form of pocket knife having the usual frame F composed of scales or side plates 10 to the outer sides of which, bolsters or end pieces 11, 11a and 12, 12a are riveted or otherwise secured, with a spring spacer member 13 interposed and secured between the scales by suitable rivets 14.

A blade 15 is pivotally mounted between the scales on a pin 16 extending through the bolsters 11, and has a suitable cam shaped hub portion 17 which co-acts with the free end 18 of the spring member 13 to yieldingly maintain the blade closed or open, all of which will be understood by those familiar with the art.

On one side of the knife, the inwardly recessed portion thereof defined by the respective scale 10 between the bolsters 11a and 12a receives a filler piece 20 of ivory, wood or other suitable decorative material which is secured to the scale by rivets 21.

The recess 22 (Figure 4) between the other two bolsters 11 and 12 on the opposite side of the knife commonly receives a filler piece, is adapted to removably receive a utility attachment A embodying this invention and composed of a spring metal support 25 on opposite sides of which are secured a sharpening element 26 of abrasive material and a cover piece 27. The cover piece 27 is preferably of the same material as the filler piece 20, and the combined thicknesses of the support 25, element 26 and cover piece 27 are equal to the thickness of the filler piece 20, so that the knife will have practically the same appearance from both sides thereof.

The support 25 is adapted to co-act with the bolsters 11 and 12 in a manner to be detachably secured in place between the bolsters. For this purpose, the bolsters have their confronting or inner end edges inwardly curved identically as indicated at 28 and 29, or of other non-rectilinear contour. These end edges are undercut or beveled to form retaining portions or lips 30 and 31, respectively.

One end of the support 25 has a lateral flange 32 covering one end of the element 26, and is outwardly curved as indicated at 33 (Figures 5 and 6) complementarily to the edges 28 and 29. Adjacent its opposite end the support 25 is laterally offset at 34 to cover the opposite end of the element 26, and from the offset 34 projects at an inclination laterally outward of the support, a resilient extension 35 the free edge of which is curved as indicated at 36 (Figures 5 and 6) complementary to the end edges 28 and 29 of the

respective bolsters. A nail mark or notch 37 in the extension 36 constitutes a means by which the attachment A can be released from the knife in a manner to be described in the operation of the invention which is as follows.

The attachment is applied to the knife by first inserting the resilient extension 35 under the lip 30, following which finger pressure is applied upon the attachment adjacent its other end until the flange 32 snaps under the lip 31, it being clear that in order for this mode of operation to be effected, the edges of the flange 32 and lips 31 co-act by a camming action, to longitudinally shift or slide the attachment in a direction away from the lips 31. As this motion of the attachment is being effected, the extension 35 flexes and rides upon the undercut or beveled surface of the lip 30.

The extension 34 will now be stressed sufficiently in a direction to react against the respective scale 10 at a fulcrum point *a* in Figures 3 and 4, so that the opposite end edge 33 of the flange 32 will be urged against the undercut or beveled surface of the retaining lip 31, thus rigidly securing the attachment against displacement from the knife.

In order to remove the attachment from the knife, it is only necessary that a finger nail be inserted in the notch 37 and force exerted upon the attachment longitudinally away from the lip 31 until the edge 33 of the flange 32 is free of the lip, at which time the urging action of the extension 35 will cause the attachment to swing laterally about the fulcrum *a* to an inclined position clear of the lip as shown in Figure 4, for easy grasping in the hand, and use of the sharpening element 26 as desired.

In applying the attachment to the knife, either end of the attachment can co-act with the lip 30 or 31, and it will be clear that by virtue of the curved edges 28 and 29 of the lips, the attachment will be confined against lateral displacement from the bolsters.

Reference will now be had to Figures 7 and 8, which disclose a modified form of attachment A' which is identical in function to the attachment A and similar in construction thereto with the exception that a cover piece 27a co-acts with metallic end members 40 and 41 secured to such cover piece 27a by rivets 42, to provide a support which is the equivalent of the support 25, a sharpening element 26a being suitably secured in the recess formed between the confronting edges of the end members 40 and 41.

The end member 40 has a free resilient extension 35a which functions in the similar manner as the extension 35. A finger nail receiving notch 37a is provided in the end member 40 for manipulation of the attachment in the same manner as previously described, so that further detailed explanation is unnecessary. The portion of the end member 40 which overlies the extension 35a acts to conceal the latter so as not to detract from the appearance of the knife.

As the bolsters 11a and 12a are identical in construction to the bolsters 11 and 12, respectively, the filler piece 20 is more rigidly secured in place by the undercut portions of the bolsters.

What is claimed is:

1. A knife of the class described comprising: a frame; end pieces on the frame co-acting therewith to define a recess between the end pieces; a filler piece received between said end pieces; said end pieces having retaining lips in confronting relationship; one end of said filler

piece having a resilient portion engageable under stress with one of said lips when the other end of the filler piece engages the other lip so as to detachably secure the filler piece to the frame; and means by which the filler piece can be released from the frame by longitudinal shifting of the filler piece on the frame in a direction away from said other lip.

2. A knife of the class described comprising: 10 a frame; end pieces on the frame co-acting therewith to define a recess between the end pieces; a filler piece received between said end pieces; said end pieces having retaining lips in confronting relationship; one end of said filler 15 piece having a resilient portion engageable under stress with one of said lips when the other end of the filler piece engages the other lip so as to detachably secure the filler piece to the frame; means by which the filler piece can be released from the frame by longitudinal shifting of the 20 filler piece on the frame in a direction away from said other lip; and means defining a fulcrum on the filler piece about which the filler piece swings outwardly from the frame under the urging action of said resilient portion when the filler 25 piece is released from said other lip.

3. A knife of the class described comprising: a frame; end pieces on the frame co-acting therewith to define a recess between the end 30 pieces; a filler piece received between said end pieces; said end pieces having undercut edges in confronting relationship and of non-rectilinear contour; the ends of said filler piece being of a contour complementary to the contour of said 35 edges, and one of said ends of the filler piece being resilient for engagement under stress with one of said edges when the other end of the filler piece engages the other of said edges, so as to detachably secure the filler piece to the frame; and 40 means by which the filler piece can be released from the frame by longitudinal shifting of the filler piece on the frame in a direction away from said other edge.

4. A knife of the class described comprising: 45 a frame; end pieces on the frame co-acting therewith to define a recess between the end pieces; a filler piece received between said end pieces; said end pieces having undercut edges in confronting relationship and of non-rectilinear 50 contour; the ends of said filler piece being of a contour complementary to the contour of said edges, and one of said ends of the filler piece being resilient for engagement under stress with one of said edges when the other end of the filler 55 piece engages the other of said edges so as to detachably secure the filler piece to the frame; means by which the filler piece can be released from the frame by longitudinal shifting of the filler piece on the frame in a direction away from said other edge; and means defining a fulcrum 60 adjacent said resilient end of the filler piece, about which the latter swings outwardly from the frame under the urging action of said resilient portion when the filler piece is released from other lip.

5. An article of the class described comprising: a handle having means defining spaced retaining portions in confronting relationship; a filler piece adapted to be received between said portions to 70 form part of the handle; means on said portions and on opposite ends of said filler piece co-actable to detachably secure the filler piece to the handle; and means by which the filler piece can be released from the handle by longitudinal shifting of the filler piece on the handle until

one end of the filler piece is free of the correlated retaining portion.

6. An article of the class described comprising: a handle having means defining spaced retaining portions in confronting relationship; a filler piece adapted to be received between said portions to form part of the handle and having a resilient end portion engageable under stress with one of said retaining portions when the other end of the filler piece engages the other retaining portion, so as to detachably secure the filler piece to the handle; and means defining a fulcrum on the filler piece about which the latter swings outwardly from the handle under the urging action of said resilient portion when the other end of the filler piece is released from said other retaining portion by a longitudinal shifting of the filler piece away from said other retaining portion.

7. An article of the class described comprising: a handle having means defining undercut lips in spaced confronting relation and of non-rectilinear contour transversely of the frame; a filler piece adapted to be received between said lips to form part of the handle and having a resilient end portion engageable with one of said lips when the other end of the filler piece engages the other lip so as to detachably secure the filler piece on the handle; said resilient end portion including a fulcrum in co-action with the handle, about which the filler piece moves away from the handle when the other end of the filler piece is released from the other lip by a longitudinal shifting of the filler piece away from said other lip.
